Des. 223,724
Patented May 30, 1972

223,724

WATER METER DIAL COVER

Paul H. Wallace, R.R. 1, Cynthiana, Ind. 47612

Filed Sept. 17, 1970, Ser. No. 25,033

Term of patent 14 years

Int. Cl. D10—07

U.S. Cl. D52—6

FIG. 1

FIG. 3

FIG. 2

FIG. 4

FIG. 1 is a top plan view of the water meter dial cover showing my new design;

FIG. 2 is a bottom plan view thereof;

FIG. 3 is a left side elevational view of FIG. 1; the right side being a mirror image thereof; and

FIG. 4 is a top perspective view thereof.

I claim:

The ornamental design for a water meter dial cover, as shown and described.
